ATTORNEY

UNITED STATES PATENT OFFICE.

LOUIS B. HARVEY, OF BUFFALO, NEW YORK.

PROJECTILE-THROWER.

1,400,058.

Specification of Letters Patent. Patented Dec. 13, 1921.

Application filed April 11, 1921. Serial No. 460,469.

To all whom it may concern:

Be it known that I, LOUIS B. HARVEY, a citizen of the United States, residing at Buffalo, county of Erie, State of New York, have invented certain new and useful Improvements in Projectile-Throwers; and I do declare the following to be a full, clear, and exact description of the same, reference being had to the accompanying drawings, and to the characters of reference marked thereon, which form a part of this application.

This invention relates to improvements in implements of warfare, the principal object of the invention being to provide a device for hurling projectiles in rapid succession and to a considerable distance, similar to a machine gun as far as the number of projectiles which may be thrown in a given time is concerned, but eliminating the need of gunpowder and the consequent high and destructive heat developed, which precludes the long continued use of firearms, since they rapidly overheat, the burnt gases corrode the metal, and they are apt to jam or explode, with disastrous consequences.

With my improved device, the above defects are eliminated, and it may be used continuously for long periods without stopping.

The projectiles may also be thrown at any angle relative to the ground, depending, as in the case of firearms, on the range desired.

The device may also be constructed as a portable structure, to be mounted on railway trucks or on wheels of its own, or it may be installed as a rigid and permanent piece of equipment.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a side elevation of my improved device.

Fig. 2 is an enlarged fragmentary cross-section taken on a line 2-2 of Fig. 1.

Referring now more particularly to the

characters of reference on the drawings, the numeral 1 denotes a frame of suitable shape and strength, in which is journaled a substantial disk 2 of any desired size, adapted to be rotated at high speed by means of an electric motor, steam or gas engine or otherwise. Rigidly mounted on the disk in radial alinement and projecting a certain distance beyond the outer periphery thereof is a hammer 3.

In vertical alinement with the hammer and there below is a flat table 4, positioned tangential to the disk, and formed with a guide member 5 adapted to ride in a slot 6 in the frame curved on an arc struck from the axis of the disk. A rack 7 of similar curvature is also formed with or fixed to the table member and is meshed with a worm 8 journaled on the frame 1, and the worm being arranged to be turned by a hand wheel 9.

Fixed to deliver on to the table and on the side thereof away from the frame 1 is a chute 10 having a supply bin or hopper 11 mounted therewith and there above, this bin being adapted to hold a number of spherical projectiles 12 and the chute being of a size to accommodate only one vertical layer of such projectiles.

The projectiles or shot are adapted to roll by gravity on to the table into the path of the hammer, their movement in this direction being limited by a back stop 13, positioned so that when a shot is abutting there against the vertical center line of the hammer and shot will lie in a common plane.

The stop member 13 is a rigid fixture, but is insulated from the table, being adapted to be highly magnetized by some such means as electric coils 14, so as to draw the shot theretoward more rapidly than if the latter moved by the force of gravity alone.

A sliding gate or shutter 15 is mounted in connection with the mouth of the chute, so that the flow of shot from the latter may be cut off at will.

In operation, the hopper is filled full of shot of a certain and predetermined size to suit all necessary conditions as heretofore described. The disk is then rotated, and when it has reached a certain speed, the shutter 15 is moved clear of the chute, allowing one shot at a time to pass into the path of the hammer 3. The latter of course strikes the shot in front thereof, and projects it

forth with a velocity and energy depending on the speed of the disk, which may be easily determined if the diameter and rim-speed of the disk are known. When the shot-table is positioned horizontally as shown in the drawing, the device is arranged for shooting at close range. For long distance range, when the shot must be projected at an upward angle which depends on the range, the table is moved ahead of the hammer the necessary amount, maintaining at all times its relation and spacing from the hammer, since its movement is concentric with the path of movement of the hammer.

15 There is very little if any danger of the shot rolling along the table when the latter is set at an angle first because of the holding power of the magnet, and secondly on account of the fact that the normal and necessary speed of the disk is so great that a shot would have no time to more than pass into the path of the hammer between revolutions of the latter.

25 The firing, if it may be so called, may be continued indefinitely as long as the driving power and the supply of shot hold out, as there is no great supply of heat generated.

30 The only part which will need renewal is the hammer, which may easily be replaced in a few minutes, and which is preferably made of the hardest yet toughest quality of steel obtainable.

35 From the foregoing description it will be readily seen that I have produced such a device as substantially fulfills the objects of the invention as set forth herein.

40 While this specification sets forth in detail the present and preferred construction of the device, still in practice such deviations from such detail may be resorted to as do not form a departure from the spirit of the invention, as defined by the appended claims.

Having thus described my invention, what

I claim as new and useful and desire to secure by Letters Patent is:

45 1. A device of the character described including a disk adapted to be rotated at a high speed, a hammer fixed to and projecting from the periphery of the disk, a table under the hammer, a bin to receive shot, a chute leading therefrom and discharging onto the table, and means for positively drawing the shot from the chute to pass into and lie in the path of movement of the hammer.

55 2. A device of the character described including a disk adapted to be rotated at a high speed, a hammer fixed to and projecting from the periphery of the disk, a table under the hammer, a bin to receive shot, a chute leading therefrom and discharging onto the table and a magnetized stop-plate on the opposite side of the table from the chute-discharge, the hammer passing therebetween.

65 3. A device of the character described including a disk adapted to be rotated at a high speed, a hammer fixed to and projecting from the periphery of the disk, a table under the hammer, a bin to receive shot, a chute leading therefrom and discharging onto the table and a stop-plate on the opposite side of the table from the chute-discharge, the plate being so positioned as to cause the shot to come to rest directly in the path of the hammer.

75 4. A device of the character set forth comprising a rotatable driven disk serving as a fly-wheel, a replaceable hammer fixed on the disk radially thereof adjacent the outer periphery thereof and projecting therebeyond, and means for feeding shot into the path of said hammer.

In testimony whereof I affix my signature.

LOUIS B. HARVEY.
